REMOTE CONTROL SWIVEL MOUNTING FOR
BOOM-SUPPORTED MICROPHONES

Edwin A. Dickinson, Verona, N. J., and George L. Fross, Valley Stream, N. Y., assignors to Reeves-Ely Laboratories, Inc., New York, N. Y., a corporation of New York

Application October 24, 1946, Serial No. 705,418

1 Claim. (Cl. 179—152)

1

This invention relates to a microphone swivel and more particularly to the type adapted to effectively support a microphone from a boom or other similar supporting structure.

In recent years, it has been the common practice in the motion picture and radio broadcasting industries to support the microphone above the actors so that the desired dialogue will be properly picked up. This apparatus usually consisted of a long pole with a hook at one end thereof and from which the microphone was suspended. This was carried from place to place as desired and turned about from time to time in order to always keep the microphone above and in front of the actor speaking, but out of the range of the camera or other stage equipment.

It is imperative that the microphone always face the actor in order that the dialogue will be properly recorded thereby. Since it is well known that the actors, particularly in the movie industry, are always moving about on the stage during the course of their performance, it is essential therefore that the microphone which is suspended from a boom or other supporting structure be supported in such a manner that the microphone proper can be turned about in order that it will face the actor at all times. This obviously necessitates a turning movement of the microphone to substantially a 360° angle since the actor may be compelled to walk about on the stage from one position to the other.

Also, since as stated previously, microphones as employed by the radio and particularly the movie industry, must be suspended from a supporting structure which is usually kept out of sight of the range of the camera, it is necessary that some arrangement be made whereby the microphone can be rotated from some remote point.

With the above in view, the primary object of this invention is to provide a microphone swivel capable of being suspended from a microphone boom or other supporting structure and which will be so connected thereon that it will be capable of rotation from a remote point and out of range of the camera when used in making sound motion pictures.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all variations and modifications as

2

fall within the spirit of the invention and the scope of the appended claim.

In the drawings:

Fig. 1 is a front elevational view showing a microphone suspended on the swivel of the invention;

Fig. 2 is a side elevational view of the microphone swivel and mounting, parts being broken away;

Fig. 3 is a bottom plan view with parts broken away; and

Fig. 4 is a detail sectional view taken on line 4—4 of Fig. 3 looking in the direction of the arrows.

15 From past experience, it has been found that the most advantageous position for the recording microphone, when recording sound motion pictures, is pointing directly down at the speaker from an angle of about 45°. This is easily accomplished when there is only one speaker or actor on the stage within range of the camera. If there are a number of speakers or actors on the stage within range of the camera, the microphone must be turned quickly from one to the other in order to follow the conversation. Also, as stated previously, the microphone should always be pointing directly at the speaker.

20 To accomplish the above, there is provided a microphone swivel including a stationary part including an upstanding eyelet 10 adapted to be connected in any well known manner to the microphone boom or other similar supporting structure. A bearing holder 11 includes a bolt 9 to which the eyelet 10 is threaded with a cover or shell 12 interposed between the bearing holder and the eyelet. In this manner, the bearing holder 11, covering or casing member 12 and eyelet member 10 are effectively retained in proper working assembly. The cover may be stamped or drawn of sheet metal or may be molded of bakelite or other plastic material.

25 A ball bearing race 13 is retained upon the lower portion of the bearing holder 11 by means of a nut 14 engaging an externally threaded shank 15 extending from the lower portion of the aforementioned bearing holder. Fitted on the ball race 13 and thereby mounted for free rotation within the casing or cover 12 is a rotor 16. A flexible element 17, as a cord or string, has one of its ends secured at 8 to the rotor 16 and is wrapped about the rotor being received as in a groove 7. The other end of element or means 17 extends outwardly to some remote point convenient for manipulation.

30 The rotor 16 is turnable on the ball bearing

mounting against the action of a spring member 18, by pulling on the element 17. One end of spring 18 is secured to a stud-like extension 19 of the threaded shank 15, as shown in Fig. 3 of the drawing, and the other end of said spring is secured to a bolt 20 carried by the rotor. As herein illustrated, the inner end of the spring is anchored by being received in a kerf or slot in the stud-like extension 19. This spring is normally under some tension and is adapted to be wound and put under further tension on the means 17 being pulled and the rotor 16 rotated.

The return rotation of the rotor 16 under the action of spring member 18 is limited by reason of stopper member 21 contacting the entrance tube 22 which is formed with the wall of the cover or casing member 12. As the eyelet 10, bearing holder 11 and casing or housing 12, are fixed together and held by a boom or the like, it will be clear that the microphone can be rotated relative to such parts, and from a remote point, by pulling on the means 17. Further, the microphone and the rotor will be returned to or toward whatever position the operator sees fit under the action of the tensioned spring member 18. This return movement will be limited by the stopper member 21 contacting the tube member 22.

A plate 23 forms the bottom closure for the swivel housing 12. The plate 23 is maintained in proper position on the casing or housing by means of insulating blocks 24 threaded or molded or otherwise secured on studs 25 threaded into the rotor member 16. Insulating blocks 24 are provided with or carry threaded studs 26 for engagement with an inverted V-shaped frame 27 supporting a microphone 28 on a pair of trunnions 29 having knurled tightening nuts. The insulating blocks 24 not only properly insulate the swivel from the microphone 14, but they also form effective means for cushioning or dampening any vibration which might be imparted to the microphone by reason of the supporting boom being moved about from place to place.

In the operation of the device, the microphone 28 is set at the desired angle and position in frame 27 and the knurled nuts of trunnions 29 tightened. The eyelet 10 supporting the swivel and microphone attached thereto is secured to the microphone boom or other supporting structure. As it is found necessary to move the microphone from one position to the other, the means 17 is manipulated to rotate the microphone on the swivel whereby to keep the microphone facing in the desired direction.

When it is found necessary to return the microphone to or toward its original position in order to keep the microphone facing in the proper direction, the cord 17 is released and, since the rotor was rotated against the action of spring 18 when the cord was pulled, the rotor will return under action of the spring to or toward its

original position. It will be seen, therefore, that the microphone can be rotated from a remote point by operation of the cord member 17 and in this manner the microphone can always be maintained facing the actor or person on the stage.

Preferably the means 17 comprises a length of stout cord so there will be no sound made by it running out of the housing or casing 12. However, the invention is not limited to such a structure since a covered or muffled chain could also be used. Additionally, it is pointed out that in lieu of a metallic spring 18 some form of elastic may be used. Thus, for silence, a length of rubber might be used to turn the microphone back to or toward normal position. Therefore, where the word "spring" is used in the following claim, it is to be taken in a comprehensive sense to include any means or construction for accomplishing the desired results.

Having thus set forth the nature of our invention, what we claim is:

In a mounting for suspending a microphone from a supporting boom and the like, a casing comprising a housing including a top and side walls and open through its underside, means on the outer side of said top wall for fixedly supporting said housing from a boom, a stud rigid with said housing and depending from the lower side of said top wall, a rotor within said housing, bearing means rotatably mounting said rotor on said stud, mounting means rigid with said rotor and extending through the lower open side of said housing and adapted to have a microphone secured thereto, said rotor having a socket opening through one side of its mid-portion and into which said stud projects, a spring in said socket and anchored at one end to said rotor and at its other end to said stud, a flexible element entering said housing through a side wall thereof and carried partly about and anchored to said rotor whereby a pull on said element will result in rotation of said rotor in one direction about said stud and in opposition to said spring and thereafter on release of said element said spring will rotate said rotor in the opposite direction, and stop means to limit turning movement of said rotor by said spring.

EDWIN A. DICKINSON.
